UNITED STATES PATENT OFFICE.

MORITZ L. MUELLER, OF SEATTLE, WASHINGTON, ASSIGNOR TO NORTHWEST BLOWER KILN COMPANY, OF SEATTLE, WASHINGTON, A CORPORATION OF WASHINGTON.

HEATING UNIT AND HEATING SYSTEM FOR KILNS.

Application filed October 11, 1926. Serial No. 140,902.

This invention relates to kilns and, to a heating unit and a heating system for the same and it has for its object to provide a novel heating apparatus, and to bring about 5 a new combination and correlation of parts, whereby marked economies in manufacture will be effected and the efficiency of the kiln will be enhanced. The nature of these economies and improvements in operation will 10 be more specifically pointed out in the following detailed description.

In the accompanying drawings—

Fig. 1 is a fragmentary horizontal sectional view of a kiln arranged for the reception of flat piled lumber.

Fig. 2 is a partial longitudinal sectional view through the kiln of Fig. 1.

Fig. 3 is a partial horizontal sectional view of a kiln arranged for the reception 20 of edge piled lumber.

Fig. 4 is a transverse, vertical sectional view, on line 4—4 of Fig. 1.

Fig. 5 is a transverse, vertical sectional view on line 5—5 of Fig. 1.

Fig. 6 is a plan view of a bank of heating pipes made up of a plurality of the units, one of which is illustrated in Fig. 5.

Fig. 7 is a fragmentary view illustrating two of the units and illustrating the staggered relation of adjacent units and

Fig. 8 is a face view of the combined supports and partitions by which the heating pipes are carried.

Like numerals designate corresponding parts in all of the figures of the drawing.

In the drawing, 5 designates the body of the kiln. A motor 6 drives through belt 7, to companion blowers 8 and 9. These blowers serve to maintain a circulation of

air in the direction indicated by the arrows.

In the forms illustrated in the Figs. 1 and 2, the air is discharged from the blowers into a central conduit 10, and upwardly through ports 11, to and through stacks of

flat piled lumber (not shown) in the manner, indicated in Fig. 3 of Patent #1,437,385, issued to me on November 28, 1922. The air passes outwardly through channels formed in the stacks of lumber toward the sides

of the kiln and downwardly through ports 12 into the longitudinally extending outside channels 13 and 14. The channels 13 and 14 communicate with the suction sides of

the blowers. Thus, a circulation in the direction of the arrows is maintained, as pre-

viously stated. In the arrangement illustrated in Fig. 3, the same disposition of the blowers is maintained but the circulation is reversed with respect to Figs. 1 and 2; that is, in this case, the motor 6^a drives 60 through a belt 7^a to blowers 8^a and 9^a. In this case, the central channel, 15, is the suction channel and the side channels 16 and 17, constitute the pressure conduits. That is, these are the channels which are connected to the discharge sides of the blowers.

Thus, the flow in this case passes from the channels 16 and 17 upwardly through ports 18 at the sides of the kiln and downwardly through stacks of edge piled lumber, (not 70 shown) in the manner indicated in Fig. 4 of my patent above referred to. The air is drawn to the suction side of the blowers through the centrally arranged ports 19.

It is manifest that if the air is to exercise a maximum drying effect it must be heated and it is in the provision of a novel heating means and in the novel disposition of this means with relation to the conduits of the kiln, that this invention particularly 75 resides.

Prior to my invention the means most generally employed for heating air in kilns of this character comprised banks of vertical steam pipes, made up of a large number 80 of pipe units of inverted U-shape, connected at their lower ends by cast iron headers. These banks of steam pipes were usually disposed either in the longitudinal air conduits of the kiln or else wholly outside of 85 the kiln and in juxtaposition to the blower casings. Other types of kilns employed longitudinally extending runs of steam pipes disposed in the air conduits.

In contradistinction to these former arrangements, the present invention contemplates the employment of heating means comprising a plurality of cross-horizontal, return bend, steam coils, disposed in such relation to both the pressure and suction 95 conduits as to project into the path of the air flowing through both of said conduits. That is, each individual coil is thus projected into the path of both the outgoing and the returning air so that the one heating unit heats the air both before it enters the blower casings and after it leaves the blower casings.

The banks of steam pipes referred to are made up of a plurality of units consisting 110

of a number of convolutions of return bend pipes, one of said units being indicated at 20 in Fig. 5. The pipes of a unit are passed through channel shaped bars 21. See Figs. 5, 6 and 8. In placing a plurality of these units together to make a complete bank of heating pipes as illustrated in Fig. 6, these channel shaped bars are butted together, so that complementally, they constitute a plate-like element, having a part of the partition separating the channel 10 from the channels 13 and 14, for example. Thus the channel shaped bars are caused to serve the double function of tying the pipes of a unit together and holding said pipes in properly spaced relation to each other and forming part of the partitions necessary to divide the suction conduits and the pressure conduits of the air circulatory system. It will be observed that the pipes of the several units are of such length as to project into all of these conduits so that the same heating element is traversed by the air both on its way to the blowers and on its way from the blowers.

By referring to Figs. 7 and 8, it will be observed that the several units are alternately vertically staggered with respect to each other. Each unit is connected at its upper end with a steam supply pipe 23, and at its lower end by suitable branch pipes 24, with a common discharge or return pipe 25. The latter may be connected by a suitable branch 26 with a steam trap or other suitable point of discharge.

Among the advantages of a heating unit of the type herein shown and described, particularly when used in relation to the kiln herein illustrated, are the following:

40. Since the sections are separate from each other any section may be removed for repair, the number of sections may be reduced or increased at will, and, in case of leakage, one section may be plugged out until it is convenient to repair it, without affecting the operation of the kiln. A heater of this character is much less expensive to construct than the types previously used in like relation, owing to the omission of the cast iron headers or bases of other types. Furthermore every part forming the heater is a standard and universally used product of pipe and steel manufacture. Such use of standard materials permits of more economical manufacture and repair than where special parts have to be renewed. Furthermore the use of a plurality of individual coil sections makes the several units considerably lighter and capable of more ready disconnection and removal for repairs than the relatively heavy parts heretofore employed for this purpose. The close fitting, upright supporting channel iron partitions, previously described, eliminate the necessity 60. of employing a special plate for this pur-

pose, necessary with the vertical heaters heretofore employed. Since the partitions formed by the combination of these upright channel irons are longitudinally movable with respect to the pipes which pass through them, or, in other words, are movable toward and from each other, it follows that these partitions may be positioned where needed according to the use of the kiln in which they are employed. That is, it will be apparent from an inspection of the drawing that the partitions are not located in the same position when flat piled lumber is being treated as when edge piled lumber is being treated and if it be desired to make a change of the method of loading during the life of the kiln, the adaptability of these partitions above referred to, constitutes a feature of marked economy in the operation of such kilns. In addition the disposition of the radiation or heater in such a way that it extends the full width of the kiln and occupies space in both the pressure and suction ducts, reduces to a minimum the space in the kiln building used for heater purposes. Further, the aforesaid location of the radiation and the adaptability to varying positions of the movable partitions, makes it possible to vary the heating effect, the air resistance and the capacity of either the suction, air or the pressure air conduit, by spreading or by drawing together the said partitions and further, permits a complete balance of heating effect, air resistance and distribution of heat at any time. Since the air passes through the heating elements in opposite directions the condensation in all of the coils is automatically balanced, since each coil, through its position, emanates the same B. t. u. heat conductance over the total surface. The fact that the steam, the condensation water and the air from the steam all travel naturally downward through the steam coils, prevents air binding and sluggish water movement and makes it the ideal radiation for dry kilns where the radiation is inaccessible and under the control of inexperienced steam engineers. This type of radiation is particularly adapted for use with high velocity air passing through the pipes, which produces more rapid condensation, high steam velocity and greater air volume in the steam, which results in less air binding. This cross-horizontal radiation is of particular utility in kilns of the type herein shown and described employing forced circulation. The provision of radiation of individual sections, variable as to number and each of which may be varied as to the number of pipes it contains, permits an adjustment of air resistance, free areas, temperature range and heating surface, in relation to the air flow, far greater than is possible with any radiation hitherto applied to drying kilns. The 130

arrangement of the radiation in the kiln in respect to the position of pipes, steam supply and condensation return, is novel, particularly by reason of the steam flow never opposing the flow of condensate as in previous types of kiln radiation. Thus, a great increase in radiation power is obtained, which shortens materially the time required to perform a given drying operation with a given amount of steam and radiation. Attention is particularly directed to the fact that the pipe supports are solid or one piece members instead of being divided in two halves consisting of several members. Hitherto one sheet construction has been unavailable in the return bend type of radiation due to the space requirements for screwing down the return bends. In my type of radiation this is accomplished by placing the channel supports back, in the center of the pipe length, while assembling the section. When the assembly of the pipe and return bends is complete the two supports are moved out to their final position where they act not only as supports but as partitions as hereinbefore described. Furthermore the use of channel shaped pipe supports not only renders it possible to employ the solid one piece members but affords a ready means of fastening one section to another with bolts or other fastening devices which pass through the abutting flanges of the respective bars.

It is to be understood that the invention is not limited to the precise construction set forth but that it includes within its purview whatever changes fairly come within either the terms or the spirit of the appended claims.

Having described my invention what I claim is:

1. In combination with a kiln comprising elongated pressure air and suction air ducts and means for maintaining a flow of air therein, of a transversely extending heating unit of such length as to lie within and substantially span such pressure air and suction air ducts, and means for supplying a heating fluid to such unit from an external source.

2. The combination with a forced circulation kiln comprising pressure air and suction air ducts, of blower means for maintaining a circulation of air through said duct, a heating unit of such length as to extend across the kiln in such position as to substantially span the pressure air and the suction air ducts whereby the air is heated, both going to and leaving the blower means, and means for supplying a heating fluid to such unit from an external source.

3. In combination with a forced circulation kiln comprising a floor, the space beneath which is divided into three conduits in one of which the air flows in one direc-

tion and in the other two of which the air flows in the opposite direction, there being ports leading from the several ducts through the floor of the kiln, of a heating means disposed within the kiln and comprising a plurality of transversely extending steam pipes of such length as to overlap and lie partly within all of said ducts and blower means outside of the point of location of the heating means adapted to maintain a circulation through said ducts, whereby the air is caused to pass through the heating means both on its way to the blower means and on its way from the blower means.

4. A structure as recited in claim 3 wherein the heating means comprise a plurality of vertically extending bars through which said pipes pass and which bars constitute supports for said pipes, the edges of said bars contacting with each other so that complementally they constitute partitions to create within the heating means ducts which constitute parts of the aforesaid ducts.

5. A forced circulation kiln of the character described comprising a floor, the space beneath which is divided into two outside ducts and a central duct, a pair of blowers to the suction sides of which the outside air ducts lead, the discharge sides of said blowers discharging into the said central duct and a heating unit comprising a plurality of horizontally disposed steam pipes extending transversely substantially entirely across the kiln inwardly of the point of discharge of the blowers and lying partly within all of said ducts so that the air is drawn through said steam pipes on its way to the blowers and is forced through said steam pipes on its way from the blowers.

6. In combination with a forced circulation kiln of the character described comprising a floor, the space beneath which is divided into outside air conduits and a central air conduit, blower means, to the discharge side of which the said outside conduits are connected and to the suction side of which the central conduit is connected, and a heating means comprising a bank of steam pipes consisting of a plurality of units, each of said units consisting of a plurality of horizontally disposed return bend pipes, said heating means being disposed across all of said conduit.

7. A structure as recited in claim 6 in combination with combined supports and partitions through which the pipes of the unit pass and which partitions constitute an extension of the walls of the said conduit.

8. A structure as recited in claim 6 in combination with combined supports and partitions through which the pipes of the unit pass and which partitions constitute an extension of the walls of the said con-

4
duit, said partitions being movable along said pipes.

9. In combination a kiln comprising a floor, the space above which constitutes the drying chamber of the kiln and the space beneath which is divided into a plurality of air ducts, means for maintaining a flow of air through said ducts, each of said ducts being provided with a plurality of ports 10 in its top spaced along its length and establishing communication between the same and the drying chamber of the kiln, a transversely extending heating unit of such length as to lie within and substantially 15 span all of said ducts, and means for supplying a heating fluid to such unit from an external source.

10. A structure as recited in claim 9

wherein the heating unit comprises a bank of horizontal steam pipes and supports for 20 said steam pipes which complementally constitute partitions, the spaces between which constitute parts of the said air ducts.

11. A structure as recited in claim 5 in combination with a plurality of vertically 25 disposed supports for the pipes through which said pipes pass, the edges of said supports abutting each other, so that complementally they constitute partitions, said partitions being aligned with the corresponding walls of the several ducts to constitute extensions thereof.

In testimony whereof I affix my signature.

MORITZ L. MUELLER.
